UNITED STATES PATENT OFFICE.

CHARLES A. MCKERAHAN, OF WILMERDING, PENNSYLVANIA.

CHURN.

1,172,618.

Specification of Letters Patent.

Patented Feb. 22, 1916.

Application filed September 29, 1914. Serial No. 864,027.

To all whom it may concern:

Be it known that I, CHARLES A. MCKERAHAN, a citizen of the United States, residing at Wilmerding, in the county of Allegheny 5 and State of Pennsylvania, have invented new and useful Improvements in Churns, of which the following is a specification.

This invention relates to churning, and more particularly to a churn of the reciprocating 10 container type.

One object of my invention is to provide a churn of the above type of simple construction and adapted to be cheaply manufactured.

15 Another object of my invention is to provide a churn having means for facilitating the charging and discharging of the container.

Other objects and advantages will appear 20 in the following more detailed description of the invention.

In the accompanying drawing, Figure 1 is a front elevation of a churn embodying my 25 improvements; Fig. 2 a front elevation of the churn, with the container in position for charging or discharging; and Fig. 3 a side elevation of the churn.

According to my invention, the churn may comprise round uprights or standards 1 30 mounted in pedestal blocks 2, a crank shaft 3 journaled in bearings in the pedestals 2, a shaft 4 provided at opposite ends with semi-cylindrical guide members 5 adapted to reciprocate on the inner portions of the uprights 1, a disk 6 carried by the shaft 4, a container 7 adapted to rest on the disk 6, a cover plate 8 provided with guide members 9 similar to the guide members 5, a forked connecting rod 10 for operatively connecting 35 the crank shaft 3 with the shaft 4, a gear 11 secured to one of the projecting ends of crank shaft 3, a gear 12 meshing with gear 11 and rotatably mounted on one of the standards 1, the gear 12 being provided with 40 a handle 13. The opposite end of the crank shaft 3 preferably carries a fly wheel 14 in order to provide a more steady and uniform churn action.

The container 7 is provided at the bottom 45 with two or more pivoted thumb screw clamps 15 for engagement with lugs 16 carried by the disk 6 and similar clamps 17 are provided at the top of the container 7 for engagement with lugs 18 on the cover plate 8.

50 A rod 19 connects the upper ends of the

standards 1 and carries an S hook 20 adapted for engagement with an eye bolt 21 secured to the cover plate 8.

At the central portion of the opposite sides of the container 7 there are bosses 22 60 having recesses therein, and thumb screws 23 have screw threaded engagement in the standards 1, the thumb screws being adapted to be screwed into the recesses of the bosses 22 when the container 7 is elevated to a 65 position in which the thumb screws are in alinement with the recesses.

In operation, the container is placed on the disk 6 and the thumb screw clamps 15 are applied to clamp the container to the 70 disk, the container is then charged, and the cover plate 8 is clamped onto the top of the container. The container is then reciprocated by turning the handle 13 until the churning is completed.

75 In order to remove the contents of the churn, the container 7 is moved by turning the handle 13 so that the recesses in the bosses 22 are brought into alinement with the thumb screws 23 and said thumb screws 80 are then screwed into the recesses so as to form trunnions for the container 7. The clamps 15 and 17 may now be loosened, the cover plate being hooked onto the hook 20 and the disk 6 caused to move away from 85 the container by turning the handle 13. It will now be evident that it is only necessary to turn the container 7 on its trunnion supports in order to discharge the contents of the container into a suitable receiving vessel. 90

After emptying, the container may be again charged, the disk 6 brought up to position and clamped, and the cover plate 8 unhooked and clamped to the top of the container. The thumb screws 23 are then 95 screwed out of the recesses in the bosses 22 and the churn is again ready for the churning operation.

Having now described my invention, what I claim as new and desire to secure by Letters Patent is:—

1. In a churn, the combination with standards, a container, a support for said container slidably mounted on said standards and removably secured to the container, of 105 trunnions carried by the standards for suspending said container independently of the support.

2. In a churn, the combination with standards, a container, means for reciprocating 110

said container within the standards, and
clamps for securing the container to said
means, of removable trunnions mounted in
said standards for supporting said container
upon disconnection from the reciprocating
means, to permit charging and discharging
of the container.

In testimony whereof I have hereunto set
my hand.

CHARLES A. McKERAHAN.
